UNITED STATES PATENT OFFICE

98,627

DESIGN FOR A COMBINED WASHING MACHINE AND WRINGER

Jacques Stanitz, Warren, Ohio, assignor to Prima Manufacturing Company, Inc., Sidney, Ohio, a corporation of Ohio

Application December 18, 1935, Serial No. 60,148

Term of patent 3½ years

To all whom it may concern:

Be it known that I, Jacques Stanitz, a citizen of the United States, residing at Warren, in the county of Trumbull and State of Ohio, have invented a new, original, and ornamental Design
for a Combined Washing Machine and Wringer, of which the following is a specification, reference being had to the accompanying drawings,
forming a part thereof.

In the drawings:

ing machine and wringer showing my new design;

Figure 4 is a section on the line 4—4 of Figure 2, looking in the direction of the arrows.

I claim:

The ornamental design for a combined washing machine and wringer substantially as shown.

JACQUES STANITZ.
